UNITED STATES PATENT OFFICE.

REXFORD M. SMITH, OF WASHINGTON, DISTRICT OF COLUMBIA, ASSIGNOR, BY MESNE ASSIGNMENTS, TO CONNECTICUT AIRCRAFT COMPANY, OF NEW HAVEN, CONNECTICUT, A CORPORATION.

FLYING-MACHINE.

1,128,379.

Specification of Letters Patent. Patented Feb. 16, 1915.

Application filed January 2, 1912. Serial No. 669,003.

To all whom it may concern:

Be it known that I, REXFORD M. SMITH, a citizen of the United States, residing at Washington, in the District of Columbia, have invented certain new and useful Improvements in Flying-Machines, of which the following is a specification.

This invention relates to flying machines of that class in which the machine is supported in flight by the dynamical reactions 10 of the air upon one or more sustaining surfaces.

One object of the invention is to provide improved means for supporting, connecting and bracing the sustaining surfaces, whereby structural strength and durability 15 may be obtained with a material reduction of head resistance.

Another object of the invention is to provide a novel construction and arrangement 20 of fins or vanes for preventing side drift or skidding of the machine and securing greater stability.

Still another object of the invention is to 25 provide a novel construction of supporting surfaces and ailerons or balancing planes, and a novel construction of the wings and frame elements of the supporting surfaces 30 to provide a free clearance or vent for the agitated air acted upon by the propeller when a forward or tractor propeller is employed.

Still another object of the invention is to 35 provide a novel construction and arrangement of devices for vertically steering the machine and maintaining the lateral and longitudinal balance thereof, which devices are 40 adapted to afford greater convenience and certainty of action and to be operated by instinctive movements of the aviator.

With these and other objects in view, the invention consists of the features of construction, combination and arrangement of parts, hereinafter fully described and 45 claimed, reference being had to the accompanying drawings, in which:—

Figure 1 is a view in side elevation of a flying machine embodying my invention. Fig. 2 is a vertical fore and aft section on 50 an enlarged scale through the supporting surfaces. Fig. 3 is a top plan view of the machine. Fig. 4 is a horizontal transverse section through one of the stanchions and fins, as indicated by the line 4—4 of Fig. 2. Fig. 5 is a front elevation of the machine.

Fig. 6 is a diagrammatic perspective view of the supporting surfaces, horizontal rudder and associated steering and controlling devices. Fig. 7 is a plan view of the vertical rudder and its controlling gear. Fig. 8 is 60 an end view of the supporting surfaces, showing a modification in the lateral balancing means. Fig. 9 is a side view of one of the wing ribs. Fig. 10 is a cross section on line 10—10 of Fig. 9.

In the illustrated exemplification the invention is shown embodied in a biplane machine, although it is to be understood that it is not limited thereto, as the essential features thereof may be employed with 70 equal efficiency upon other types of multi-plane machines or upon machines of the monoplane type.

Referring to the drawings, 1 designates the body or main frame of the machine, 75 preferably in the form of a stream-line boat-shaped car or nacelle, the tail portion of which carries suitable fixed horizontal and vertical stability fins 2 and 3 and horizontal and vertical rudders 4 and 5, and is provided with a trail skid or fender 6 of any preferred type. As shown, the horizontal rudder 4 preferably has a central cut-out space through which the vertical rudder 5 projects and in which said vertical rudder is laterally movable. The forward end of the nacelle is mounted upon a suitable chassis 7 including front skids 8 and cushioned launching and landing wheels 9.

Within the bow of the nacelle is arranged in practice a motor (not shown) of any preferred construction, the shaft 10 of which carries a tractor propeller 11. In the cockpit of the nacelle are placed seats 12 and 13 disposed one in rear of the other for the 95 accommodation of the aviator and a passenger. The seat 12 is arranged sufficiently in rear of the center of gravity and pressure so that the weight of the aviator and controls will approximately balance the 100 the weight of the motor, while the seat 13 is arranged in line with the center of gravity and pressure so that the presence or absence of a passenger will not influence the longitudinal balance of the machine. With 105 this type of construction duplicate sets of controls may be employed for the independent or conjoint use of the occupants of the seats, if desired.

In the embodiment of the invention in a 110

biplane structure, as disclosed, the supporting planes or surfaces 14 and 15 are duplicates in form and construction, each comprising a pair of wings 16 and 17 spaced at 5 their inner or proximate edges to provide a fore-and-aft air gap 18. These gaps are arranged in the path of the air impelled upwardly and downwardly and traveling rearwardly from the propeller, thus permitting 10 the disturbed air to have free vent through the supporting surfaces and preventing the same from disturbing the air compressed by the wings, accumulating between the supporting surfaces and increasing the head resistance, or varying the angle of incidence 15 or flying attitude of the machine. The wings, which may have any suitable fore-and-aft curvature, are formed of a fabric or other suitable covering secured to a frame 20 composed of ribs 19 fixed to longitudinal spars or bed rails 20, each rib being formed of superposed strips 21 and 22 of spruce or other suitable material spaced by the rails 20 and suitable fillers 23. The rear end of 25 the upper strip 21 of each rib terminates in rear of the rear end of the lower strip 22 and rests upon a strip 24, preferably of hickory or other suitable tough and flexible material. The forward end of this strip 24 30 abuts against the rear end of the strip 22 and fits within a socket formed by a U-shaped stirrup 25 secured by fastenings 26 to an adjacent filler block, whereby the strips 22 and 24 are held in proper relation. 35 The strips 24 are held from possible displacement by fastenings 27 entering the filler blocks to which the stirrups are secured, whereby any damaged strip may be readily removed and a new strip applied in 40 its place. The strips 24 render the wings flexible longitudinally in rear of the strips 21 for a vibratory air-shedding action. The spars or bed rails extend continuously the full length of each plane, the bed rails of 45 the lower plane being suitably fastened to the nacelle. In the embodiment of the invention in a monoplane structure, the wings of the supporting surface may be mounted upon the nacelle in any suitable manner and 50 spaced as required for free passage of the air from the propeller.

The wings of the supporting surfaces are rigidly connected and held in spaced relation by a single set of stanchions or struts 55 28 arranged at suitable intervals apart and about midway of the width of the rigid body of the plane, at or near the camber line and in coincidence with the centers of gravity and pressure. These stanchions are 60 suitably secured at their ends to the frames of the respective surfaces, and are rigidly fixed thereto by braces or stays 29. Preferably each brace or stay is formed of a piece of tubing bent into V-form, its vertex being flattened and passed through an opening

30 extending through the stanchion between its front and rear edges, while the divergently arranged arms of said brace are suitably fastened, as at 31, to the frame of the contiguous wing. By this construction the 70 supporting surfaces and stanchions are not only directly connected, but are also mutually reinforced and braced in front and rear of the plane of the stanchions, whereby a strong and rigid union is secured. This enables one of the two rows of stanchions or struts commonly employed to be dispensed with, together with the usual wire trusses, with a consequent reduction of head resistance. If desired the braces and braced ends 80 of the stanchions may be inclosed by coverings 32, forming triangular fins disposed parallel with the line of flight and operating to prevent lateral skidding or side drift of the machine when in flight, also to reduce 85 head resistance.

The wings of the supporting surfaces are symmetrically curved, and the flexible rear portions of the respective wings are bisected or divided in a fore and aft direction, as at 90 33, forming relatively rigid and flexible inner and outer portions. The flexible outer portions 34, 34^a, 35, 35^a of the respective wings constitute ailerons, balancing planes or balancing surfaces lying normally in the 95 plane of the respective supporting surfaces and the ailerons 34 and 35 are capable of being flexed downward to a positive angle of incidence while the ailerons 34^a and 35^a are similarly capable of being flexed upwardly 100 to a negative angle of incidence. Each wing thus comprises a body having a rigid fore portion and a flexible rear portion, the latter consisting of an inner section normally uncontrolled and adapted to flex or vibrate 105 under air pressures and an outer section adapted to be positively controlled and adjusted to maintain the lateral balance of the machine.

The ailerons are designed to be operated 110 by a pair of right and left hand controlling levers 36 and 37, each universally mounted or intermediately pivoted to swing fore and aft on an axis 38 and to swing laterally on an axis 39, said levers being so relatively 115 arranged as to be operated independently or in unison. The lower arm of the lever 36 has attached thereto a wire or cable 40 leading over guide pulleys 41 to a point above the aileron 35^a, and the upper arm of said lever has attached thereto a wire or cable 42 leading over one or more guide pulleys 43 to a point below the aileron 35, said cables 40 and 42 being respectively attached 120 by branches or bridles 40^a and 42^a to the outer corner portions of the respective ailerons, whereby when the lever 36 is swung laterally to the left the wire 40 will be relaxed while the wire 42 will be drawn upon 125 to bend the aileron 35 downward to a posi- 130

tive angle of incidence; and whereby when said lever is swung laterally to the right the wire 42 will be relaxed while the wire 40 will be drawn upon to bend the aileron 35 upward to a negative angle of incidence. The lever 37 is similarly connected by corresponding designated controlling connections to the ailerons 34 and 34^a, so that when said lever is swung laterally to the right the wire 40 will be relaxed and the wire 42 drawn upon to bend the aileron 34 downward, while upon a reverse lateral motion of said lever the wire 42 will be relaxed and the wire 40 drawn upon to bend the aileron 34^a upward. It will thus be understood that the ailerons may be independently flexed by the control levers, and as said ailerons are capable of being flexed, in a plane perpendicularly to the plane of the supporting surfaces it will be evident that in balancing and banking the machine the adjustment of the ailerons to reverse positive and negative angles of incidence at the opposite sides of the machine will result in securing increased efficiency of balancing control, since a positive lifting action will be obtained at one side and a positive depressing action at the other side. By this means the well known objections to constructions in which one balancing surface is drawn down to a positive angle of incidence to secure a lift and the opposite surface merely released to assume a negative angle of incidence are avoided. Moreover, since the ailerons are movable perpendicularly to the plane of the supporting surfaces, they are adapted to be adjusted without affecting or destroying the normal symmetry of said surfaces, thus preventing the same from being unduly strained, warped out of shape or setting up an undue head resistance, as in constructions of that kind in which the surfaces are helicoidally bent or warped.

In practice, the levers 36 and 37 are arranged to be grasped in the right and left hand of the operator so that they may be independently or simultaneously adjusted, and so that instinctive motions on the part of the operator will result in a proper adjustment of the balancing surfaces. If, for instance, the machine should tilt laterally toward the right the tendency of the operator to lean in the opposite direction will result in the surface 35 being bent downwardly to secure a lift at the depressed side and the surface 34^a bent upwardly to secure a depressing action at the elevated side, while if the machine should tilt in the opposite direction the tendency of the operator to lean toward the high side will result in the surface 35^a being elevated to secure a depressing action at the elevated side and the surface 34 being depressed to secure a lifting action at the low side. By this arrangement of the levers and connections the natural instinct of the operator to move toward the upturned side in every instance is taken advantage of, thus reducing liability of mistakes in adjusting the controls. The use of independent controlling devices also adapts the ailerons at either side to be adjusted independently of those at the opposite side to more sensitively correct any slight tilting tendencies which may occur and may be corrected without objectionable increase of head resistance. For these reasons, the construction and arrangement of parts disclosed is preferred in a biplane type of machine, although, as shown in Fig. 8, the ailerons at either side may be suitably coupled, as by means of a connecting link 44, for movement in unison in the same direction. In the adaptation of the balancing structure to a machine of the monoplane type, the ailerons or balancing surfaces at each side may be regarded as parts of single units each coupled by connections with the associated lever whereby it may be adjusted either upward or downward to a desired angle of incidence. This modification would involve merely the connection of the control wires from each lever to the aileron in such manner that a movement of the lever in one direction will flex the aileron upward, while a reverse movement of the lever will flex the aileron downward.

The horizontal rudder 4 is adjusted by means of the levers 36 and 37 and to this end is shown provided with upper and lower pairs of crank arms 45 and 46 connected with the respective levers by cords or cables 47 and 48. The forward ends of these cables are attached to each lever above and below the axis 38, the cable 47 from the upper arm 45 being connected with the lower arm of the lever and the cable 48 from the lower arm 46 being connected with the upper arm of the lever. To permit of such arrangement the cables are intermediately crossed and passed over pairs of direction pulleys 49 and 50. Thus a manually backward or forward movement of either lever, or both levers in unison, will result in an upward or downward movement of the rudder 4, the use of two levers allowing greater or less power to be employed as required. It will be observed that the described arrangement of the cables also provides for a utilization of the instinctive movements of the aviator in adjusting the rudder to correct any fore and aft instability, the aviator adjusting the levers in each instance toward the elevated point of the machine and away from the depressed point of the machine in order to adjust the rudder to restore the longitudinal balance.

While I have shown and described a construction and arrangement of superposed supporting surfaces, having wing tips

at the right and left hand margins thereof, the tips of the upper surface being flexible or warpable downwardly and the tips of the lower surface flexible or warpable upwardly, 5 together with controlling levers and connections between the same and the wing tips, whereby the sets of tips may be simultaneously adjusted, it is evident that I may employ simply the wing tips 34^a and 35^a, which 10 are independently flexible or warpable upwardly to a negative angle of incidence, so that the effective area and angle of incidence at the high side of a laterally unbalanced machine may be decreased, while the effective area and angle of incidence at the low side remains unimpaired, to restore the machine to a state of balance or equilibrium.

The vertical rudder 5 is provided with laterally extending crank arms 51 and 52 to 20 which are attached the rear ends of cords or wires 53 and 54, which are crossed intermediate of their length and passed around direction pulleys 55 and 56, the forward end of the cable 53 leading from the right hand 25 arm 51 being connected with the left hand arm of an intermediately pivoted control lever 57, while the forward end of the cable 54 leading from the left hand arm 52 of the rudder is connected with the right hand arm 30 of said control lever. This arrangement of the controlling connections also provides for a natural adjustment of the control lever on the part of the aviator, as the aviator swings the lever toward that side of the machine lying in the direction of the turning 35 motion.

Having thus described the invention, what I claim as new is:—

1. In a flying machine, a pair of curved, 40 superposed supporting surfaces, each comprising a body rigid to substantially equal degrees in front and rear of its camber point and flexible in rear of its rigid portion, a row of struts extending between said surfaces coincident with the camber line thereof, and bracing members connecting each strut with the respective supporting surfaces, each of said braces being united to the strut at an intermediate point and thence 45 having relatively diverging arms extending toward the surface to which it is attached and connected with the rigid portion of said surface at substantially equidistant points in front and rear of the strut.
2. In a flying machine, a pair of curved, 50 superposed supporting surfaces, each comprising a body rigid to substantially equal degrees in front and rear of its camber line, and flexible in rear of said rigid portion, a row of struts extending between said surfaces coincident with the camber line, and 55 braces connecting the struts with the respective surfaces, each brace being substantially of V-form and connected at the vertex portion thereof with the strut and having its

arms extending divergently toward the surface to which it is attached at substantially equal angles in front and rear of the strut and attached to the rigid portion of said surface at substantially equal distances in front and rear of the strut.

3. In a flying machine, a pair of curved, superposed supporting surfaces each comprising a body rigid to substantially equal degrees in front and rear of its camber line and flexible in rear of its rigid portion, a single set of struts extending between said surfaces coincident with the camber line, substantially V-shaped braces connecting each strut with the respective supporting surfaces, each of said braces being connected at its vertex portion with the strut and having its arms diverging at equal angles toward the surface to which it is attached in front and rear of the strut and secured to the latter at points in front and rear of the strut and equidistantly therefrom, and a sheathing of material about each brace and inclosing a portion of the strut between the center of the brace and the coacting supporting surface, whereby upper and lower sets of substantially triangular stability vanes are formed between said surfaces.

4. In a flying machine, a pair of superposed supporting surfaces, a single set of intervening struts, braces intermediately connected with the struts and connected with said surfaces in front and rear of said struts, and a covering about each brace and the adjoining portion of the strut, whereby upper and lower sets of stability vanes are formed between the surfaces.

5. In a flying machine, a pair of superposed supporting surfaces, a single row of intervening struts extending between said surfaces, upper and lower sets of braces of substantially V-form passing intermediately through the struts and thence having their diverging arms extending in front and rear of the struts toward the respective surfaces and secured thereto, and a sheathing of material about each brace and inclosing the portion of the strut between the center of the brace and the coacting supporting surface, whereby upper and lower sets of stability vanes are formed between said surfaces.

6. In a flying machine, a supporting surface comprising longitudinal bars, ribs each comprising strips arranged above and below the bars, the lower strip being of less length than the upper strip and the latter having its rear edge extending downwardly at an angle, and a supplementary strip detachably fastened in position and forming a continuation of the short lower strip extending beyond the rear end of the upper strip lying in contact therewith, and a covering of suitable material inclosing said bars and ribs.

7. In a flying machine, a supporting surface comprising a pair of superposed planes, the wings of the upper plane having portions adapted to be flexed downwardly and the wings of the lower plane having portions which are adapted to be flexed upwardly, right and left hand intermediately pivoted levers, a down-pulling connection between the upper arm of the right hand lever and the flexible portion of the right hand wing of the upper supporting surface, an up-pulling connection between the lower arm of the right hand lever and the flexible portion of the right hand wing of the lower plane, and similar connections between the left hand lever and the flexible portions of the left hand wings of the upper and lower planes.

8. In a flying machine, superposed supporting surfaces provided on opposite sides of the longitudinal center of the machine with superposed balancing portions respectively adjustable upward and downward to negative and positive angles of incidence, a pair of right and left hand controlling devices, a lifting connection between the left hand controlling device and the lower left hand balancing portion, a depressing connection between the left hand controlling device and the upper left hand balancing portion, and corresponding connections between the right hand controlling device and the lower and upper right hand balancing portions.

9. A flying machine comprising a chassis, a nacelle, supporting surfaces above and below the plane of the nacelle, the lower supporting surface including frame bars fastened to the chassis and nacelle, a single set or row of stanchions rigidly connecting the superposed wings of the supporting surfaces at a point about in line with the center of gravity and pressure, and braces connecting said stanchions with said surfaces in front and rear of the former.

10. In a flying machine, a horizontal rudder, lateral balancing surfaces, a pair of juxtaposed right and left hand levers having fore and aft and lateral swinging movements, and flexible connections between both

of said levers and the horizontal rudder and 50 between the levers and the respective right and left hand balancing surfaces.

11. In a flying machine, a horizontal rudder, lateral balancing surfaces, a pair of oppositely arranged right and left hand levers 55 intermediately pivoted to swing on horizontal and transverse axes, crossed cables connecting the upper and lower arms of each lever with the horizontal rudder below and above the horizontal axis of said rudder 60 and connections between said levers and the balancing surfaces.

12. In a flying machine, superposed supporting surfaces, provided on opposite sides of the longitudinal center of the machine 65 with superposed balancing portions respectively adjustable upward and downward to negative and positive angles of incidence, a pair of right and left hand normally vertical intermediately pivoted levers movable laterally in either direction, a lifting connection between the lower arm of the left hand lever and the lower left hand balancing portion, a depressing connection between the upper arm of said lever and the upper left hand 75 balancing portion, and corresponding connections between the right hand lever and the lower and upper right hand balancing portions.

13. In a flying machine, a horizontal rudder, lateral balancing surfaces, a pair of juxtaposed right and left hand fore and aft and laterally movable levers operable independently or in unison, connections for adjusting the horizontal rudder when said levers are moved fore and aft independently or conjointly, and connections between the levers and balancing surfaces for controlling the latter independently or conjointly through independent or conjoint lateral 80 movements of said levers.

In testimony whereof I affix my signature in presence of two witnesses.

REXFORD M. SMITH.
